INVENTOR.

Milo H. Beck

BY

Geo. P. Kimmel ATTORNEY.

UNITED STATES PATENT OFFICE.

MILo H. BECK, OF OILTON, OKLAHOMA.

TRAFFIC SIGNAL.

Application filed September 3, 1924. Serial No. 735,594.

To all whom it may concern:

Be it known that MILo H. BECK, citizen of the United States, residing at Oilton, in the county of Creek and State of Oklahoma, has invented certain new and useful Improvements in Traffic Signals, of which the following is a specification.

This invention relates to traffic signal devices for installation in roadways, preferably at the crossings of streets or other roadways, and at railway and trolley line crossings, and has for one of its objects to provide a device of this character of simple construction and yieldably supported in vertical position across the roadway and over which a vehicle may be moved to depress the same, and with means for automatically restoring the device to vertical position after the vehicle passes.

Another object of the invention is to provide a device of this character operative by vehicles approaching from either direction, and which will not interfere with the ordinary traffic of the roadway.

With these and other objects in view the invention consists in certain novel features of construction as hereinafter shown and described and then specifically pointed out in the claims, and in the drawings illustrative of the preferred embodiment of the invention.

Figure 1 is a side elevation of the improved device installed upon a roadway or pavement, the signal bearing device being in elevation and the pavement in section.

Figure 2 is a transverse section with the improved device in depressed position.

Figure 3 is a section, enlarged, on the line 3—3 of Figure 1, looking in the direction of the arrow.

Figure 4 is a section, enlarged, on the line 4—4 of Figure 1, looking in the direction of the arrow.

The improved device may be installed wherever warning to passing vehicles is required, for instance at street or roadway crossings, railway or trolley line crossings and the like, to notify the operators of the vehicles that a crossing is near, but for the purpose of illustration, the improved device is shown installed in a section of pavement, for instance asphalt or cement, and indicated at 10.

The improved device includes a pair of spaced supports 11 embedded in the pavement, preferably in a mass of concrete or

the like, and indicated at 12. At its upper end each of the supports 11 is provided with a half bearing 13, with a detachable cap 14 for each half bearing.

Journalled in the bearings is a rotatable member 15, and attached to the latter is a legend bearing plate or frame 16.

Coiled around the member 15 adjacent to the bearings are springs 17, one end engaged at 18 in the member 11 or its half bearing 13, and the other end extended and bent at 19 to bear over the adjacent portions of the member 16. The springs are reversely coiled, with the terminals 19 bearing against opposite sides of the member 16, one spring thus exerting its force to move the plate in one direction, and the other spring to move the plate in the opposite direction. The springs thus operate against each other to hold the plate yieldably in vertical position, and automatically return it to vertical position after being turned down from either direction.

The member 16 will be provided with any suitable designating data, such as the word "Stop", as shown, or other words, or in some distinctive color or combination of colors or design to render the member conspicuous to an approaching vehicle.

The device will be installed at any convenient point. It may be installed directly in the line of the traffic of the roadway so that most of the passing vehicles will pass over it, or located at one side and operative only by a small portion of the passing vehicles but in plain view of all, approaching from either direction.

The improved device is simple in construction, can be inexpensively manufactured, and of any desired size or material or combination of materials.

The preferred embodiment of the invention is disclosed in the drawings and set forth in the specification, but it will be understood that modifications within the scope of the claimed invention may be made in the construction without departing from the principle of the invention or sacrificing any of its advantages.

Having thus described my invention what I claim is:

1. A traffic signal including spaced carrier devices adapted to be supported in a roadway, a signal bearing element mounted for oscillation relative to said carrier devices, a spring coupled to one of said car-

rier devices and operative against one face of the signal bearing element, and a spring coupled to the other carrier device and operative against the other face of said signal bearing element, said springs coacting to maintain the signal bearing element yieldably in vertical position.

2. A traffic signal including spaced carrier devices adapted to be supported in a roadway, and each provided with a bearing at the upper end, a support mounted for

rotation in said bearings, a signal bearing element attached to said support, a spring coupled to one of said carrier devices and operative against one face of the signal bearing element, and a spring coupled to the other carrier device and operative against the other face of said signal bearing element. 15

In testimony whereof, I affix my signature hereto.

MILO H. BECK.
